Patented July 15, 1975

235,927

COMBINED LEG AND ARM SPLINT

George E. Moore II, Hollywood, Fla., assignor to
All Orthopedic Appliances, Inc., Miami, Fla.

Filed Feb. 14, 1974, Ser. No. 442,645

Term of patent 14 years

Int. Cl. D24—04

U.S. Cl. D83—1 J

FIG. 1

FIG. 2

FIG. 3

FIG. 1 is a plan view of a combined leg and arm splint showing my new design;

FIG. 2 is a plan view of the opposite side thereof; and

FIG. 3 is a perspective view shown positioned about a leg which is shown in the dotted lines for illustrative purposes only.

I claim:

The ornamental design for a combined leg and arm splint, substantially as shown and described.
